UNITED STATES PATENT OFFICE.

FREDERICK CONLIN, OF BETHLEHEM, PENNSYLVANIA, ASSIGNOR TO THE MERWARTH METALLIC GASKET COMPANY, OF SOUTH BETHLEHEM, PENNSYLVANIA, A CORPORATION OF PENNSYLVANIA.

DESIGN FOR A GASKET OR PACKING.

SPECIFICATION forming part of Design No. 35,534, dated December 31, 1901.

Application filed April 16, 1901. Serial No. 56,172. Term of patent 14 years.

To all whom it may concern:

Be it known that I, FREDERICK CONLIN, of Bethlehem, in the county of Northampton, and in the State of Pennsylvania, have invented and produced a certain new and original Design for a Gasket or Packing; and I do hereby declare that the following is a full, clear, and exact description thereof, reference being had to the accompanying drawings, in which—

Figure 1 is a plan view of a gasket or packing, showing my new design. Fig. 2 is a cross-section of the same.

Letters of like name and kind refer to like parts in both figures.

The object of my invention is to provide a design for gaskets or packing for the joints of pipes or other apparatus; and to this end

said invention consists in the design for a gasket or packing, substantially as herein shown and described.

The leading feature of my design consists in the shape or configuration, which, as illustrated, comprises an inner ring A, an outer ring B, and three intermediate rings C.

Having thus described my invention, what I claim is—

The design for a gasket or packing, substantially as shown and described.

In testimony that I claim the foregoing I have hereunto set my hand this 8th day of April, 1901.

FREDK. CONLIN.
